DESIGN FOR A Porthole VENTILATOR

Edward Rambusch, Harrison, N. Y., assignor to
Rambusch Decorating Company, New York,
N. Y., a corporation of New York

Application May 2, 1944, Serial No. 113,444

Term of patent 3½ years

(Cl. D71—1)

To all whom it may concern:

Be it known that I, Edward Rambusch, a citizen of the United States of America and a resident of Harrison, in the county of Westchester and State of New York, have invented a new, original, and ornamental Design for a Porthole Ventilator, of which the following is a specification, reference being had to the accompanying drawing, forming a part thereof.

In the drawing:

Figure 1 is a side elevational view of the porthole ventilator showing my new design;

Figure 2 is an elevational view of the same taken from the right or left of Figure 1; and

Figure 3 is a fragmentary sectional view of the same taken on the line 3—3 of Figure 2.

I claim:

The ornamental design for a porthole ventilator, as shown.

EDWARD RAMBUSCH.
